CLAIM

The ornamental design for an oil bottle for electronic atomizing device as shown and described.

DESCRIPTION

FIG. 1 is a perspective view of an oil bottle for electronic atomizing device according to an embodiment of our design; FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view of an oil bottle for electronic atomizing device according to another embodiment of our design;

FIG. 10 is another perspective view thereof.

FIG. 11 is a front elevational view thereof;

FIG. 12 is a rear elevational view thereof;

FIG. 13 is a left side view thereof;

FIG. 14 is a right side view thereof;

FIG. 15 is a top plan view thereof; and,

FIG. 16 is a bottom plan view thereof.

The broken lines in the drawings depict portions of the oil bottle for electronic atomizing device that form no part of the claimed design.

The oblique shade lines in the drawings show transparency.
